Kansas City, Mo.

Application May 1, 1939, Serial No. 270,993

8 Claims. (Cl. 62—131)

This invention relates to air conditioning apparatus in the nature of portable room coolers that may be used as a table or similar article of furniture, as the same is functioning to circulate and cool the air within the room.

The primary object of this invention is to provide an effective, efficient, durable and economical air conditioning device that may be constructed of sheet metal or the like, and which has a specially formed ice tank, one wall of which is disposed in the path of travel of a current of air directed thereagainst by a fan, which is uniquely housed and effectively located so that the cooler may be utilized as an article of furniture while in operation.

This invention has for a further aim, the provision of a room cooler of a portable nature which is so designed as to collect from the air passing therethrough, such excess moisture as will be objectionable to the end that the humidity of the room being cooled, is lowered simultaneously with the lowering of the temperature.

A yet further object of this invention is to provide a room cooler having a fan and ice tank, both of which are assembled in such relation as to change the direction of air currents created by the fan, which change of direction occurs only after the current originated by the fan has struck the walls of the ice tank upon which the moisture from the air is collected because of the temperature differential.

Further aims of this invention include the specific form of the parts which are built into the room cooler and which include the plurality of legs that serve as supports for the cooler and a yieldable mount for the motor; a frusto-conical form of the ice tank, a portion of which is disposed within an inverted conical reservoir; the pedestal which is of a length sufficient to cooperate with the blower fan therein in establishing vertical air currents having sufficient force to change their direction of travel and extend into the room an appreciable distance after impinging upon the outer face of the ice tank; and the removable platform which forms a cover for the ice tank and a table top when the room cooler is employed as an article of furniture.

Further objects including the specific manner of constructing a room cooler in accordance with the preferred form of the invention, will appear during the course of the following specification, referring to the accompanying drawings wherein:

Figure 1 is a side elevation of a room cooler embodying the invention.

Fig. 2 is a top plan view of the same, parts being broken away for clearness.

Fig. 3 is a vertical central sectional view through the room cooler, taken on line III—III of Fig. 1.

Fig. 4 is an inverted plan view of the apparatus; and,

Fig. 5 is an enlarged fragmentary detailed sectional view through the marginal edge of the platform which forms the cover of the ice tank.

In practice the component parts of the air conditioner, or room cooler, should be formed of sheet metal or analogous material, and the conical, hollow pedestal 6 is open at its upper and lower ends and of sufficient length to adequately house the means for creating a current of air upwardly therethrough. This means is in the nature of a motor 8 on the shaft 10 of which is mounted a series of blades 12, which when rotated by the motor, create a draft upwardly through pedestal 6 and against the outer surface of ice tank 14 which is of a special form and disposed in a particular manner with respect to pedestal 6.

Upwardly and outwardly extending brackets 16 are carried by pedestal 6 and in the preferred embodiment four of these brackets 16 are employed. Brackets 16 should be as narrow as possible so that the space between the upper circumscribing edge of pedestal 6 and ice tank 14 is unrestricted to allow the outward movement of air.

Ice tank 14 is frusto-conical and inverted so that the base or end of greatest diameter is at the top of the apparatus.

Brackets 16 carry ring 18 and an out-turned marginal edge 20 of tank 14 rests upon ring 18, as more clearly illustrated in Fig. 5. To create the desired seal at this joint, a resilient sealing bead 22 is fastened to this marginal edge 20. Bead 22 may be made from a rubber tubing which is split longitudinally and pressed over margin 20.

Platform 24 has a depending annular flange 26 secured to the under-surface thereof, to prevent lateral displacement of platform 20 when the parts are in the operative position, shown in the drawings. Platform 24 not only serves as a cover for ice tank 14, but creates a table top of attractive design.

The height of the room cooler, or the distance of platform 24 from the floor, should be agreeable to articles of furniture which the cooler simulates, and when the apparatus is employed as a coffee table for example, the distance of platform 24

24 from the floor is not as great as when the device is to be used as a card table or the like.

The diameter of ice tank 14 at its upper end is substantially greater than the diameter of reservoir 6. The end of small diameter of tank 14 is closed so that ice 28 may be contained within tank 14 in a place where the vertical currents of air will be separated therefrom only by the downwardly and inwardly inclined wall 30 of tank 14. 10 Bottom wall 32 of tank 14 has a drain opening 34 formed therein for the reception of a drain tube 36, one end of which carries a valve 38 positioned within easy reach of the operator of the cooler.

15 Valve 38 is diametrically opposed to valve 40 which is on the end of drain pipe 42 that communicates with reservoir 44, from which the collected condensate is drawn from time-to-time.

The plurality of relatively narrow fixtures 46 serve to mount reservoir 44 in a place where a 20 small portion of ice tank 14 is disposed therein. A continuous annular space 47 formed between wall 30 of tank 14, and the upper end of the downwardly and inwardly inclined wall of reservoir 44, permits condensate to flow by gravity 25 downwardly along the outer face of wall 30 and into reservoir 44.

The lower end of pedestal 6 is held above the supporting surface or floor 48, by a number of legs 50, each of which is specially formed to carry 30 a foot 52. One end of each leg 50 extends inwardly and upwardly to be joined together by plate 54 upon which is mounted motor 8. Legs 50 are preferably constructed of resilient metal such as spring steel so that the motor is yieldably mounted and cushioned thereby to prevent 35 as far as possible, the production of objectionable noise and vibration.

In the illustrated embodiment of the room cooler four legs 50 are shown and plate 54 is 40 located on the vertical central axis of the apparatus, so that the axis of rotation of blades 12 is in alignment with the common vertical axis of tank 14 and reservoir 44.

The operation of the room cooler is clear to 45 one skilled in the art. While motor 8 is driving blades 12, air is drawn into the hollow pedestal 6, through the open lower end thereof, and directed upwardly therethrough against the outer surface of the inclined wall of reservoir 44 and also 50 against the downwardly and inwardly inclined wall 30 of ice tank 14. The space between the circumscribing wall of pedestal 6 is great enough to accommodate the volume of air which is forced upwardly by the fan. As the air leaves blades 12 55 of the fan, its velocity will increase because of the restriction and the force exerted will definitely insure that all of the air passing upwardly through pedestal 6 will impinge against the outer face of ice tank 14. No moisture will be 60 collected by the air passing through the apparatus—on the contrary, excess moisture will be withdrawn therefrom because of the low temperature of wall 30 due to the presence of ice 28.

The form and location of ice tank 14 such as 65 to overhang the upper end of pedestal 6 and the air of the room being cooled which is not drawn through pedestal 6, is circulated about the exposed cool wall 30 to augment the cooling action.

Obviously, fans of different capacity may be 70 employed to speed the velocity of air currents passing through the cooler and apparatus embodying the invention may be made of materials best suited to the conditions met, all without departing from the spirit of the invention or scope 75 of the appended claims.

Having thus described the invention, what is claimed as new and desired to be secured by Letters Patent is:

1. A room cooler of the character described comprising a hollow pedestal open at its upper and lower ends; a plurality of legs on the lower end of the pedestal to hold the same spaced above the floor; a plurality of brackets on the upper end of the pedestal; an inverted frusto-conical ice tank mounted on the brackets above the top of 10 said pedestal; a reservoir in the pedestal below the ice tank; and means within the pedestal for creating a current of air upwardly therethrough and against the inclined side of the ice tank.

2. A room cooler of the character described 15 comprising a vertical hollow cylindrical pedestal open at its upper and lower ends; a plurality of legs on the lower end of the pedestal to hold the same spaced above the floor; a plurality of upwardly extending brackets on the upper end of 20 the pedestal; an open top receptacle in the pedestal having an annular, downwardly and inwardly inclined side wall converging to a point on the axis of the pedestal; an inverted frusto-conical ice tank mounted on said brackets and 25 having its end of smallest diameter extending into the said receptacle with the annular side wall thereof in spaced relation with the side wall of said receptacle; and a fan within the pedestal for creating a current of air upwardly there- 30 through and against the inclined sides of the receptacle and said tank.

3. A room cooler of the character described comprising a vertical hollow cylindrical pedestal open at its upper and lower ends; a plurality of 35 legs on the lower end of the pedestal to hold the same spaced above the floor; a plurality of upwardly extending brackets on the upper end of the pedestal; an open top receptacle in the pedestal having an annular, downwardly and inwardly 40 inclined side wall converging to a point on the axis of the pedestal; an inverted frusto-conical ice tank mounted on said brackets and having its end of smallest diameter extending into the 45 said receptacle within the annular side wall thereof in spaced relation with the side wall of said receptacle; and a fan within the pedestal for creating a current of air upwardly therethrough and against the inclined sides of the receptacle and said tank, said ice tank having its said 50 inclined side wall spaced from the upper end of the pedestal and extending laterally outwardly beyond the pedestal thereabove.

4. A room cooler of the character described comprising a vertical hollow cylindrical pedestal 55 open at its upper and lower ends; a plurality of legs on the lower end of the pedestal to hold the same spaced above the floor; a plurality of upwardly extending brackets on the upper end of the pedestal; an open top receptacle in the pedestal having an annular, downwardly and inwardly 60 inclined side wall converging to a point on the axis of the pedestal; an inverted frusto-conical ice tank mounted on said brackets and having its end of smallest diameter extending into the 65 said receptacle within the annular side wall thereof in spaced relation with the side wall of said receptacle; and a fan within the pedestal for creating a current of air upwardly therethrough and against the inclined sides of the 70 receptacle and said tank, said ice tank having its said inclined side wall spaced from the upper end of the pedestal and extending laterally outwardly beyond the pedestal thereabove, said ice tank having a platform thereon closing the end of 75

greatest diameter and extending outwardly beyond the edge of the wall thereof.

5. A room cooler of the character described comprising a hollow pedestal open at its upper and lower ends; a plurality of legs on the lower end of the pedestal to hold the same spaced above the floor; a plurality of brackets on the upper end of the pedestal; an inverted frusto-conical ice tank mounted on the brackets above the top of said pedestal; a reservoir in the pedestal below the ice tank; and means within the pedestal for creating a current of air upwardly therethrough and against the inclined side of the ice tank, said legs being inwardly bent to form a support for the 10 means for creating the current of air.

6. A room cooler of the character described comprising a hollow pedestal open at its upper and lower ends; a plurality of legs on the lower end of the pedestal to hold the same spaced above the floor; a plurality of brackets on the upper end of the pedestal; an inverted frusto-conical ice tank mounted on the brackets above the top of said pedestal; a reservoir in the pedestal below the ice tank; and means within the pedestal for 15 creating a current of air upwardly therethrough and against the inclined side of the ice tank, said means for creating a current of air being a motor and fan blades driven thereby, said legs being formed of resilient material and each having a 20 portion spaced above the floor for creating a yieldable support for the said motor.

7. A room cooler of the character described comprising a vertical hollow cylindrical pedestal open at its upper and lower ends; a plurality of legs on the lower end of the pedestal to hold the same spaced above the floor; a plurality of upwardly extending brackets on the upper end of the pedestal; an open top receptacle in the pedestal having an annular, downwardly and inwardly 25 inclined side wall converging to a point on the axis of the pedestal; an inverted frusto-conical ice tank mounted on said brackets and having its end of smallest diameter extending into the said receptacle within the annular side wall thereof in 30 spaced relation with the side wall of said receptacle; and a fan within the pedestal for creating a current of air upwardly therethrough and 35

against the inclined sides of the receptacle and said tank, said ice tank having its said inclined side wall spaced from the upper end of the pedestal and extending laterally outwardly beyond the pedestal thereabove, said ice tank having a platform thereon closing the end of greatest diameter and extending outwardly beyond the edge of the wall thereof, said fan having its axis on the vertical axis of the said ice tank and the receptacle whereby the upwardly directed air current is divided into evenly distributed radial paths beginning at points of impingement of the upwardly directed air current on the outer surface of the ice tank.

8. A room cooler of the character described comprising a vertical hollow cylindrical pedestal open at its upper and lower ends; a plurality of legs on the lower end of the pedestal to hold the same spaced above the floor; a plurality of upwardly extending brackets on the upper end of the pedestal; an open top receptacle in the pedestal having an annular, downwardly and inwardly inclined side wall converging to a point on the axis of the pedestal; an inverted frusto-conical ice tank mounted on said brackets and having its end of smallest diameter extending into the said receptacle within the annular side wall thereof in spaced relation with the side wall of said receptacle; and a fan within the pedestal for creating a current of air upwardly therethrough and against the inclined sides of the receptacle and said tank, said ice tank having its said inclined side wall spaced from the upper end of the pedestal and extending laterally outwardly beyond the pedestal thereabove, said ice tank having a removable platform thereon closing the end of greatest diameter and extending outwardly beyond the edge of the wall thereof, said ice tank having a resilient sealing head around the edge thereof in engagement with the under side of said platform, said platform having a depending annular flange thereon circumscribing the said edge of the ice tank for precluding lateral displacement of the platform.
